UNITED STATES PATENT OFFICE.

GEORGE H. CLARK, OF WASHINGTON, DISTRICT OF COLUMBIA, ASSIGNOR TO MARCONI
WIRELESS TELEGRAPH COMPANY OF AMERICA, A CORPORATION OF NEW JERSEY.

ADJUSTMENT OF WAVE LENGTHS.

1,323,155.

Specification of Letters Patent. Patented Nov. 25, 1919.

Application filed January 18, 1915. Serial No. 2,799.

To all whom it may concern:

Be it known that I, GEORGE H. CLARK, a citizen of the United States, of Washington, District of Columbia, have invented 5 new and useful Improvements in Adjustment of Wave Lengths, of which the following is a specification.

My invention relates to telegraphy, telephony, or like systems in which the energy 10 employed is in the electro-radiant form for space systems or in the form of high frequency oscillations for conductive systems.

Heretofore in the practical and commercial use of systems such as above referred to, it 15 has been impossible with the prior art apparatus available to change the transmission or reception quickly and promptly from a setting for one wave length or frequency to a setting for another wave length or frequency, because involving more than a single movement or adjustment of an apparatus, in fact involving a plurality of independent movements for tuning and adjusting operations with resulting loss of considerable time which is a serious disadvantage 25 and a chief hindrance in the satisfactory operation of apparatus of this character.

It is the object of my invention to provide, either at the transmitting or receiving 30 station, or both, apparatus whereby settings for different wave lengths or frequencies may be made by a single operation of switching mechanism which shall at the same time insure proper or desired coupling between inductively related oscillation circuits.

To these ends I have devised the system and apparatus hereinafter described and 40 constituting an embodiment of my invention.

For an illustration of one of the forms my invention may take reference is to be had to the accompanying drawings, in 45 which:

Figure 1 is a diagrammatic view illustrating a typical transmitting apparatus to which my invention may be applied.

Fig. 2 is a diagrammatic view illustrating electrical connections and co-operating switching mechanism for carrying out my invention in transmitting apparatus.

Fig. 3 is a diagrammatic view similar to Fig. 2 when used in receiving apparatus.

Fig. 1 shows a typical transmitting appa-

ratus to which reference is made for an explanation of my invention.

Referring to this figure, G is an alternating current generator or other suitable source of current connected in circuit with the primary *p* of a step-up transformer, the primary circuit being controlled by the usual transmitting key *k*. The high tension secondary *s* of the step-up transformer has its terminals connected to either side of the spark gap *g* which may be of the simple type indicated or may be of the quenched gap type, or any other suitable type. The gap *g* is in circuit with the condenser or capacity *K* and the variable portions of the primary *P* of the oscillation transformer, the circuit *PKg* being here shown as a closed oscillation circuit. The open or antenna circuit comprises a variable portion of the secondary *S* of the oscillation transformer, a variable portion of the loading inductance *L*, beyond the inductive influence of the primary *P*, the antenna or aerial conductor *A*, and the earth connection *E*, a radiation meter *M*, such as a hot wire ammeter, being included for purposes of convenience.

When it is desired to transmit energy of a certain frequency or wave length, the variable or sliding contact in the primary circuit is moved to such point on the primary *P*, as for example the point 1, which will insure the primary circuit producing oscillations of the desired frequency, corresponding with wave length No. 1. This setting 85 may be determined by a wave meter, by calculation, or otherwise. The open or antenna circuit is then attuned to this same frequency or wave length, when the coupling between *P* and *S* is loose, by adjusting the 90 variable contacts on *S* or on *L* until the meter *M* gives a maximum reading. Then by making the coupling between *P* and *S* closer and of such character as is to be employed in transmitting energy having wave length No. 100 1 the rider or contact sliding on the loading inductance *L* will have to be moved to some new position until the wave meter indicates but a single maximum in the resonance curve, and the adjustment is further 105 varied until with this single maximum in the resonance curve the meter *M* indicates a maximum reading for that particular coupling. And in this connection the point 1 in the primary *P* may have to 110

be varied slightly from its first setting. However, by these well-known methods the setting of the inductance L , of secondary S and of primary P are determined for the 5 wave length No. 1. Similarly for another wave length, say No. 2, the settings will be at the points indicated by 2; the settings for a third wave length by 3, and for the 4th wave length by 4.

- 10 In all cases the necessary or desired inductance in the antenna or open circuit for any given wave length can be so proportioned between the secondary S and the loading inductance L that the same mechanical coupling, that is, same physical or mechanical distance or relation between the primary P and secondary S can be obtained for all wave lengths. In making this adjustment of the relative amounts of inductance in S and L for any wave length, if the 15 coupling is too close, the number of turns in S is reduced and the number of turns in L is increased, and conversely if the coupling is too loose, the number of turns in L 20 is reduced, and the number of turns in S is increased.

By my invention I provide switching mechanism, a single movement of which will transfer the movable contacts on P , S and L 25 to the proper points for transmission of these various wave lengths while maintaining the desired or proper coupling between the primary P and the secondary S , this coupling being generally such as will cause 30 a transmission of maximum energy from the closed oscillation circuit to the open antenna circuit.

In Fig. 2 this same general arrangement is shown except that the primary p of the 35 step-up transformer and its circuit are omitted, and there is added the switching mechanism referred to and additional variable inductances or variometers in the open and closed circuits for sake of convenience.

- 40 The points 1, 2, 3 and 4 for the four different wave lengths are indicated as in Fig. 1. From the four points 1, 2, 3 and 4 of the primary P connections are made to the four contacts P^1 , P^2 , P^3 and P^4 adapted to 45 be engaged by the switch arm P^a . Similarly the four points 1, 2, 3 and 4 on the secondary S are connected respectively with the four switch contacts S^1 , S^2 , S^3 and S^4 , with 50 which the movable switch arm S^a is adapted to engage. And similarly the four points 55 1, 2, 3 and 4 on the inductance L are connected with the four switch contacts L^1 , L^2 , L^3 and L^4 with which the switch arm L^a is adapted to engage. Inductance L is here 60 shown as divided into two parts, though a greater number may be employed if desired, in order that when one part of the inductance is not in use it may be cut out of circuit (or short circuited as hereinafter described) to prevent energy consumption by 65

such idle portion. For this purpose connections are made from the adjacent ends of the two inductance portions by conductors a and b with the switch contacts c and d which are adapted to be bridged, when both 70 parts of the inductance are to be used, by the switch contact e . The antenna A is connected with the switch arm L^a . And the switch arm S^a connects to the earth E through the radiation meter M and, if desired, an additional variable inductance L^a , which may be set at once for all wave 75 lengths of a group, may be employed.

And in the primary circuit an additional inductance L^b may be employed if required 80 or desired.

The switch arms P^a , S^a , L^a and e are mechanically connected together, as by member or shaft f , which may be provided with a hand wheel or other operating device h . 85

In this figure are shown two condensers or banks of condensers K , K which may be connected in parallel or in series with each other under various circumstances. Switching mechanism for changing these condenser connections comprises stationary switch contacts i , j , m , n , o , and the blank q . The two movable contacts r and t are mechanically connected together but insulated from each other and mechanically connected 90 with the operating mechanism for the switches previously described, this connection causing the contacts r and t to be in position shown, and thereby connect the condensers K , K in parallel with each other, 95 for the three right hand positions of the switch P^a , but when the switch P^a engages with contact P^1 , the contacts t , r are shifted toward the left, r remaining in contact with j and engaging the blank q , while t remains 100 in contact with n and connects the same to o , in which case the condensers K , K are in series with each other in the primary circuit, the switch P^a being connected with the contact m . The object of this is to have less 105 capacity in circuit for the shorter wave length or lengths so that the corresponding coöperating inductance of the primary circuit will be a substantial part of the primary P . And in reverse movement of the 110 switch arm P^a , the switch contacts t and r are restored to the position shown and occupy such position for all positions of the switch arm P^a when engaging contacts P^2 , P^3 and P^4 . 115

With the parts in the position illustrated in Fig. 2 the connections are such as to transmit wave length No. 3, the amount of inductance L , the coupling between P and S , and the number of turns or length of P in 120 the primary circuit being proper for this wave length. When shifting to any of the other positions the other and corresponding wave lengths will be transmitted while maintaining the coupling at the proper and de- 125 130

sired amount and the amount of inductance in the closed and open circuits at the proper amounts.

When the switch arm L^s moves to the left 5 on to contact L^2 or contact L^1 the upper part of the inductance L will not be in use, and it is therefore open circuited for both these positions by the withdrawal of the switch contact e from bridging relation with 10 contacts c and d .

While the apparatus thus far described has been transmitting apparatus it will be understood that the same functions may be procured for receiving apparatus.

15 Thus in Fig. 3 Fig. 2 has been reproduced, but in place of the apparatus shown in the primary circuit of Fig. 2 receiving apparatus is shown. And what was the primary P of Fig. 2 is now in reality the secondary 20 of an oscillation transformer which is included in circuit with the variable capacity K^2 a variable inductance or variometer V and a wave responsive device or detector W in shunt with which is connected a telephone receiver T or other suitable instrumentality.

Here again it will be understood that for receiving on different wave lengths the operator need merely turn the hand wheel 30 h to any of the positions, and then by varying V and K^2 maximum response will be obtained by tuning.

In both transmitting and receiving apparatus above described, the total inductance 35 of the primary circuit and the total inductance of the secondary circuit are simultaneously changed for the different wave lengths by a single movement of the switching apparatus, and for each of these different values 40 of total inductance of primary circuit and of total inductance of secondary circuit, the optimum coupling is maintained without relative movement between the primary and secondary coils.

45 As well understood in this art, the coefficient of coupling between primary and secondary circuits is equal to the mutual induction divided by the square root of the product of the total inductance of the primary circuit multiplied by the total inductance of the secondary circuit. By my invention the coefficient of coupling, or as generally termed, "the coupling," is maintained at the same value for the different wave 50 lengths with a given separation between the primary and secondary coils for all those wave lengths. The switching apparatus changes the total inductances of primary and secondary circuits, the connections from the 55 switch points to the primary, secondary and inductance being to such points in them that the coupling is maintained the same for the different wave lengths.

While with my apparatus hereinbefore 60 described the change from one wave length

or frequency to another is accomplished by a single movement, as by a single actuation of the hand wheel h for a given position of the secondary S with respect to the primary P , or a given separation between them, my 70 invention comprehends also the accomplishment of the same result for different relative positions of or separations between the secondary S and the primary P , both when such separation is changed by manually 75 shifting one or the other and when such separation is changed or varied by mechanical means.

The shaft f need not be rotated or actuated manually but may be actuated by a 80 suitable motive device electrically or otherwise controlled from a distance to cause the shaft f to partake of the proper degrees of rotation for shifting the mechanism to the proper positions for the various wave 85 lengths or frequencies.

What I claim is:

1. The combination with the primary and secondary of an oscillation transformer and their current paths, of switches and connections therefrom to said primary and secondary for maintaining a predetermined coupling between them for each of a plurality of different oscillation frequencies, and means common to said switches for actuating them in unison. 95

2. The combination with the primary and secondary of an oscillation transformer, of an inductance in circuit with one of them, switches and connections with said primary, 100 secondary and said inductance for simultaneously procuring predetermined couplings between said primary and secondary and the requisite amount of inductance for each of a plurality of oscillation frequencies, 105 and means common to said switches for actuating them in unison.

3. The combination with the primary and secondary of an oscillation transformer, of a switch for each for varying the same, the 110 variation in one being complementary to the variation of the other for maintaining a predetermined coupling, and means causing said switches to move in unison.

4. The combination with the primary and secondary windings of an oscillation transformer, of additional inductance, switches for varying said inductance and a winding of said transformer and means causing said switches to move in unison with each other, 115 120 the variations caused by said switches being complementary to each other for maintaining a predetermined coupling for a plurality of different wave lengths.

5. The combination with a winding of an 125 oscillation transformer, of an inductance in circuit therewith, a switch connected with said winding and said inductance and serving to simultaneously complementarily alter the amount of each in circuit for maintain- 130

- ing a predetermined coupling for each of a plurality of wave lengths.
6. The combination with the primary and secondary of an oscillation transformer, of 5 switches and connections therefrom to said primary and secondary for simultaneously maintaining a predetermined coupling and adjusting both primary and secondary circuits to different wave lengths, and means 10 common to said switches for actuating them in unison.
7. The combination with the primary and secondary of an oscillation transformer occupying a predetermined position with respect to each other, of switches and connections therefrom to said primary and secondary for maintaining a predetermined coupling between them for each of a plurality of different wave lengths, and means 15 common to said switches for actuating them in unison.
8. The combination with the primary and secondary of an oscillation transformer occupying a predetermined position with respect to each other, of an inductance in 20 circuit with one of them, and switches and connections with said primary, secondary and said inductance for simultaneously maintaining a predetermined coupling between 25 the primary and secondary circuits and adjusting said circuits to different wave 30 lengths, and means common to said switches for actuating them in unison.
9. The combination with the primary and secondary of an oscillation transformer occupying a predetermined position with respect to each other, of an inductance in circuit with one of said transformer windings, and switches having connections with said 35 inductance and with the winding in circuit therewith for simultaneously maintaining a predetermined coupling between primary and secondary circuits and adjusting the circuit of said inductance to different wave 40 lengths, and means common to said switches for actuating them in unison.
- 45 10. The combination with the primary and secondary of an oscillation transformer,
- of an inductance in circuit with one of them, a switch and connections therefrom to said primary for varying the amount of said primary in circuit, a second switch and connections therefrom to said secondary for varying the amount of said secondary in circuit, a third switch and connections therefrom to 50 said inductance for varying the amount of said inductance in circuit, means mechanically coupling together said switches, said connections being so adjusted that the circuits may be set to various wave lengths by 55 movement of said means without changing the predetermined coupling between the circuits.
11. The combination with a transformer, of adjusting means therefor, tuning means 60 in both primary and secondary circuits of said transformer, means common to said tuning means and to said adjusting means for operating them simultaneously to change the wave length of the circuits while maintaining them in tune with each other and maintaining the coupling constant.
12. The combination with a transformer, of adjusting means therefor, primary and secondary circuits therefor, variable inductance in one of said circuits, means common 65 to said adjusting means and to said inductance for varying them simultaneously to vary the period of said one of said circuits while maintaining the coupling between the 70 two circuits constant.
13. The combination with a transformer, of adjusting means therefor, tuning means in circuit with said transformer, and means common to said tuning means and said adjusting means for operating them simultaneously to vary the wave length while maintaining a constant co-efficient of coupling.
- In testimony whereof I have hereunto affixed my signature in the presence of the two 75 subscribing witnesses.
